ASSIGNORS TO WEATHERBEST STAINED SHINGLE COMPANY, OF NORTH TONA-
WANDA, NEW YORK, A CORPORATION OF NEW YORK

SHINGLE HANDLING MACHINE

Application filed October 16, 1930. Serial No. 489,106.

Our machine relates in general to shingle handling machines and in particular to a machine for the feeding and brushing of stained shingles.

5 It is well known to those skilled in the art that in the process of drying stained shingles, bubbles are often formed on the surface, which when dried, flake off, leaving the surface mottled and resulting in a 10 shingle which is not uniformly stained. We have discovered that if shingles are brushed immediately after stained or sometime before they are dry, all such bubbles will be removed and the entire surface of the 15 shingle will be uniformly stained. One of the drawbacks, however, to machine brushing of the wet stained shingles has been the difficulty in providing suitable means for handling the shingles during the operation.

20 The principal object of our invention has been, therefore, to provide means, whereby the wet shingles may be quickly and accurately fed to the brushing means.

Furthermore, it has been an object to 25 provide a device of this nature in which a tier of shingles may be fed at one time.

Moreover, our device provides efficient means for brushing the shingles on both sides thereof at the same time.

30 The above objects and advantages have been accomplished by the device shown in the accompanying drawings, of which:

Fig. 1 is a side elevation of our complete device.

35 Fig. 2 is a top face view thereof, portions thereof for clearness of illustration being omitted.

Fig. 3 is a transverse sectional view, taken on line 3—3 of Fig. 2.

40 Fig. 4 is an enlarged, fragmentary, sectional view, taken on line 4—4 of Fig. 2.

Fig. 5 is an enlarged, fragmentary, sectional view, taken on line 5—5 of Fig. 2.

Our device comprises a base 10 which is 45 preferably mounted upon casters 11 so that it may be conveniently wheeled about. Carried by the base 10 is the framework of the device, consisting of vertical members 12 and inclined members 13. Arranged in 50 interspaced relation with each of the in-

clined members 13 and projecting some above these members is a guide plate 14, and between these plates is arranged a grating formed by a plurality of interspaced bars 15. These bars are preferably inclined somewhat with respect to the guide plates 14, for purposes to be hereinafter described and they are supported by suitable cross members 21 mounted upon angle iron members 22. Arranged above the bars 15 of the grating and near their lower ends is the hopper 16 of our device. This hopper has its back wall 17 inclined at an angle as shown in Figs. 1 and 4, whereby a plurality of shingles 18 placed within the hopper 60 will slide downwardly until their butts are in engagement with the back wall. Side walls 19 are provided for keeping the shingles in place, and these side walls are 65 spaced apart preferably the width of the maximum size bundle of shingles being treated.

Arranged below the hopper is a feeder 70 bar rest plate 25. This rest plate is in interspaced relation with the lower edge of the back plate 17 of the hopper and forms a bottom for the hopper for supporting the butt end of the shingle. A feeder bar 26 is 75 slidable upon this plate and passes through the space formed between it and the bottom edge of the rear wall of the hopper. This feeder bar is designed to engage with the butts of the lowermost tier of shingles and to quickly move them forwardly and upwardly until they pass by the upper edge 80 of the rest plate 25 and fall onto the bars 15 of the grating.

The feed bar 26 is operated so as to have 85 a quick forward movement which is sufficiently impactive to knock the lower tier of shingles from the hopper without feeding those which are on top of and supported by such lower tier. This mechanism comprises a cam 27 mounted at each side of the machine and carried by the main drive shaft 90 95 28. Engageable with each of these cams is a feeder arm 29. Each feeder arm is pivotally carried at its lower end 30 in the framework 10 of the machine and is formed in its upper end 31 with an elongated slot 32, 100

each of which engages with a pin 33 carried one at each end of the feeder bar 26, whereby when the feeder arms 29 are actuated, the bar will be operated thereby. The 5 cams 27 have their surfaces so arranged that there is a gradual rise in the direction of rotation when the feeder arms 29 are being returned to their normal positions. The surface of each cam, however, has an 10 abrupt drop in the radially formed surface 34. Each of the feeder arms is provided with a cam engaging lug 35, and when this lug reaches the end of the curved surface of the cam, it will be drawn quickly to 15 the starting point of the curved surface of the cam and carry with it the feeder bar. Each of the feeder arms is kept in contact with the surface of the cam by means of a helical spring 36. Each spring is conveniently arranged on the side of the inclined members 13 and each is carried by an adjusting screw 37, whereby its tension may 20 be regulated.

Mounted at one end of the main shaft 28 25 is a sprocket wheel 40 which is connected by means of a suitable chain 41 to a gear reduction unit 42. This unit is driven by means of an electric motor 43, and a switch 44 is carried in a convenient position by one of 30 the inclined members 13. Both the gear reduction unit 42 and motor 43 are preferably carried by an extension on the base 10, and these parts, for clearness of illustration, have been omitted from Fig. 2. The 35 sprocket wheel 40 is preferably mounted so that it is frictionally engaged with the drive shafts 28, in a well known manner, so that if the mechanism should be stalled for any reason, the sprocket would slip and permit 40 the motor to continue running until shut off by an attendant.

Arranged near the top of the machine is a feed drum 44 which is mounted upon a drum shaft 45. Also mounted upon the 45 drum shaft 45 are two sprockets 46, one arranged at each side of the drum and between the guide plates 14 and inclined members 13. The main drive shaft 28 also carries a sprocket wheel 47 at points between the 50 guide plates 14 and inclined members 13, and connecting each of the sprocket wheels 47 and 46 is a feed chain 48. A plurality of carrier bars 50 are secured to the chains 48 and extend across the machine and engage 55 with the butt ends of the tiers of shingles which have been knocked out of the hopper. A stop plate 51 is arranged across the machine underneath the hopper and follows substantially the contour of the line of travel 60 of the carrier bars around the sprockets 47, whereby shingles which have been knocked out of the hopper will slide down the bars 15 of the grating and be brought to rest by contact with this plate until such time as a 65 feed bar reaches them. The feed drum 44

is so arranged that the upper surfaces of the bars 15 of the grating, if projected, would be tangent to the outer surface thereof so that the shingles will be smoothly fed to and upon the drum. The drum may be provided with a series of interspaced grooves 55, thus forming circular ridges 56 which are in registering position with the feed bars 15. 70

Arranged between the upper end of the grating and the feed roller 44 are the brushes 60 and 61 of our device. These brushes are of a length substantially equal to the width of the machine between the guide plates 14, and each of them is provided with the back plate 62 having its ends pivotally carried at one end by a link 63 and at the other end by a link 64. The links 63 and 64 are pivotally carried at points midway their length by means of brackets 65, which are secured to the inclined members 13. A brush cam 66 is carried at one end of the drum shaft 45, and the link 63 is provided with a roller 67 for engagement with a groove 68 formed in the cam 66. This groove is formed so that the roller is caused to be moved back and forth as the cam rotates, wherebv the brushes will be reciprocated in opposite directions back and forth across the upper and lower surfaces of each tier of shingles as they are being passed therebetween. 75 80 85 90 95

From the foregoing it will be clear that, when for instance, a batch of shingles is placed within the hopper 16 with their butt ends toward the rear wall 17, they will fall to the bottom of the hopper, resting upon the rest plate 25 with their tips supported by the bars 15 of the grating. When the motor 43 is put into operation, the feeder bar will be operated by the engagement of the lugs 35 of the feeder arms 29 with the curved surfaces 34 of the cams 27. When the cams have been rotated to a position where the lugs 35 pass the curved surfaces and reach the radially formed surfaces 34 of the cams, the arms will be quickly drawn upwardly by means of the springs 36, which will cause the feeder bar 26 to be brought against the butts of the lowermost tier of shingles of the bundle with a sharp impact, thus knocking this tier of shingles forwardly to or slightly beyond the 110 position shown in Fig. 4, where the butts will be at or beyond the forward edge of the rest plate 25 and from which position they will fall onto the bars 15 of the grating and be in such a position that one of the carrier bars 50 will engage them and carry them upwardly along the bars 15. Should the tier of shingles which has just been discharged from the hopper have a tendency to slide downwardly on top of the bars 15, they will be arrested in their downward movement by the stop plate 51. The tier of shingles which has just been ejected from the hopper will be carried upwardly along the top surfaces of the bars 15 of the grate and fed in 115 120 125 130

between and through the brushes 60 and 61 where their surfaces will be brushed by the reciprocating movement of the brushes, thus removing any bubbles or blisters which may 5 have formed on the surfaces of the shingles and giving to the shingles uniformly stained surfaces. Since the carrier bars are arranged in the same plane as the shingles being fed, they will pass between the brushes 10 and carry the shingles on up to the center of the drum 44. As the shingles are being discharged from the drum they will be projected into a suitable hopper (not shown) arranged preferably immediately in front of 15 and slightly below the drum.

Obviously, some modifications of the details herein shown and described may be made without departing from the spirit of our invention or the scope of the appended 20 claims, and we do not, therefore, wish to be limited to the exact embodiment herein shown and described, the form shown being merely a preferred embodiment thereof.

Having thus described our invention, what 25 we claim is:

1. A shingle handling machine comprising a hopper for supporting the shingles being fed, said hopper being formed with an open front and provided with a back wall, such 30 back wall being so inclined that when the lowermost shingle is being fed, the remaining shingles will be held therein by gravity, a rest plate arranged under the feed hopper, the forward edge of the plate being arranged 35 a short distance in front of the back of the hopper for supporting the butt ends only of the shingles, a feeder bar movable in an inclined plane upon the rest plate and under the hopper for engaging the lowermost shingle 40 therein, and means for quickly operating the feed bar on its forward stroke.

2. A shingle handling machine comprising a hopper for supporting the shingles being fed, said hopper being formed with an open 45 front and provided with a back wall, such back wall being so inclined that the shingles remaining in the hopper will be held therein by gravity, a feeder bar movable under the shingles for engaging the butt of the lower- 50 most shingle, and means for quickly operating the feeder bar on its forward stroke, whereby the lowermost shingle is ejected from the hopper.

3. A shingle handling machine comprising 55 a hopper for supporting the shingles being fed, said hopper being formed with an open front and provided with a back wall, such back wall being so inclined that the shingles remaining in the hopper will be held therein 60 by gravity, a feeder bar movable under the shingles for engaging the butt of the lowermost shingle, means for quickly operating the feeder bar on its forward stroke, a grating arranged under the hopper in an in- 65 clined plane, and carrier bars movable over

the grating for carrying the shingles discharged from the hopper upwardly along the grating.

4. A shingle handling machine comprising a hopper for supporting the shingles being fed, said hopper being formed with an open front and provided with a back wall, such back wall being so inclined that the shingles remaining in the hopper will be held therein by gravity, a feeder bar movable under the shingles for engaging the butt of the lowermost shingle, means for quickly operating the feeder bar on its forward stroke, a grating arranged under the hopper in an inclined plane, carrier bars movable over the grating for carrying the shingles discharged from the hopper upwardly along the grating, and a stop plate located under the hopper, whereby the downward movement of the shingles will be arrested until they are engaged by a carrier bar.

5. A shingle handling machine comprising a hopper for supporting the shingles being fed, said hopper being formed with an open front and provided with a back wall, such back wall being so inclined that the shingles remaining in the hopper will be held therein by gravity, a feeder bar movable under the shingles for engaging the butt of the lowermost shingle, and means for quickly operating the feeder bar on its forward stroke comprising a feeder arm arranged at each side of the feeder bar, and feeder cam for each of the arms, each cam being designed to produce a quick forward movement of the feeder bar and a gradual return movement thereof.

6. A shingle handling machine comprising a hopper for supporting the shingles being fed, said hopper being formed with an open front and provided with a back wall, such back wall being so inclined that the shingles remaining in the hopper will be held therein by gravity, a feeder bar movable under the shingles for engaging the butt of the lowermost shingle, means for quickly operating the feeder bar on its forward stroke, a grating arranged under the hopper in an inclined plane, a feed chain arranged at each side of the inclined plane, and a plurality of carrier bars carried by the chains and movable under the hopper for engaging the butt ends of the shingles as they are discharged from the hopper.

7. A shingle handling machine comprising a hopper for supporting the shingles being fed, said hopper being formed with an open front and provided with a back wall, such back wall being so inclined that the shingles remaining in the hopper will be held therein by gravity, a feeder bar movable under the shingles for engaging the butt of the lowermost shingle, means for quickly operating the feeder bar on its forward stroke, a grating arranged under the hopper in an inclined plane,

plane, a guide plate arranged at each side of the grating, and carrier bars movable over the grating for carrying the shingles discharged from the hopper upwardly along the 5 grating.

8. A shingle handling machine comprising a hopper for supporting the shingles being fed, said hopper being formed with an open front and provided with a back wall, such 10 back wall being so inclined that the shingles remaining in the hopper will be held therein by gravity, a rest plate arranged under the feed hopper, a feeder bar movable in an inclined plane upon the rest plate and under 15 the hopper for engaging the lowermost shingle therein, and means for quickly operating the feeder bar on its forward stroke.

In testimony whereof, we have hereunto signed our names.
